UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAYBOLT STRUCTURE.

1,399,033.

Specification of Letters Patent.

Patented Dec. 6, 1921.

Application filed September 12, 1919. Serial No. 323,361.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Staybolt Structures; and we do hereby declare the following to be a full, clear, and exact 10 description of the invention, such as will enable others skilled in the art to which it appertains to make and use the same.

This invention relates to improvements in staybolt structures for boilers,—one object 15 of the invention being to provide a bearing sleeve or member for the bolt head, which shall have a universally movable or adjustable mounting in the boiler sheet and which shall be capable of being mounted in the 20 boiler sheet so that its outer end will be substantially flush with the outer face of the boiler sheet, or be capable of being mounted on the boiler sheet so that it will project outwardly beyond the boiler sheet, 25 and to provide efficient means whereby the said universally movable or adjustable bearing sleeve shall be firmly secured to the boiler sheet after it shall have been accurately adjusted to insure proper alinement 30 of the points of connection of the staybolt with the respective boiler sheets.

With this and other objects in view, the invention consists in certain novel features of construction and combinations of parts 35 as hereinafter set forth and pointed out in the claims.

In the accompanying drawings; Figure 1 is a sectional view partly in elevation showing an embodiment of our invention illustrating one way in which the bearing sleeve or member may be mounted in the boiler sheet, and Fig. 2 is a similar view showing another manner in which the bearing sleeve or member may be mounted in the boiler 45 sheet.

1 represents an outer boiler sheet and 2 the inner sheet of a boiler.

In the embodiment of our invention shown in Fig. 1, the outer boiler sheet is provided 50 with an opening 3, a portion 4 of the wall of which may be made tapering and straight throughout a portion of the thickness of the sheet, and another portion, 5, of the wall of said opening is made rounded to 55 form a seat on which a bearing sleeve or

member 6 may have a universally movable or adjustable mounting.

The bearing sleeve or member is made interiorly with a rounded seat 7 for the rounded head 8 at the outer end of a staybolt 9—the inner end of the latter being secured to the inner boiler sheet 2 in any suitable manner. The body portion of the bearing sleeve or member in which the head of the staybolt is mounted is curved exteriorly, as at 10. The upper or outer end of the sleeve is made with an annular enlargement 11, the outer face of which is curved or rounded transversely as at 11^a so as to afford a universally movable mounting for the sleeve on the curved portion 5 of the wall of the opening in the boiler sheet when it is desirable to mount the sleeve in the outer boiler sheet in such manner that its outer end shall be substantially 75 flush with the outer face of said boiler sheet, as shown in Fig. 1.

When the bearing sleeve or member 6 shall have been properly adjusted on its seat in the boiler sheet to insure accurate 80 alinement of the points of connection of the staybolt with the respective boiler sheets, the head 11 of said bearing sleeve or member will be welded to the boiler sheet, as shown at 12. The weld 12 is effected with 85 the use of a suitable welding alloy occupying the groove formed by a portion of the enlargement 11 and the straight portion 4 of the opening in the boiler sheet.

The enlarged outer end portion 11 of the 90 bearing sleeve or member 6 may be threaded interiorly to receive a hollow threaded plug or closure 13 having an angular portion 14 to receive a wrench, said angular portion lying flush with the outer face of 95 the outer boiler sheet and the outer end of the bearing sleeve or member. A gasket 15 may be located between the inner end of the plug and a shoulder 16 within the sleeve or bearing member 6.

When it is desired to mount the bearing sleeve in the opening in the boiler sheet so that it will project outwardly therefrom instead of inwardly as shown in Fig. 1 and still preserve the universally movable or 105 adjustable feature of the device, a portion of the wall of the opening 3^a in the boiler sheet will be made to afford a rounded seat 17 on which the rounded exterior portion 10 of the bearing sleeve or member has a 110

universally movable or adjustable mounting as shown in Fig. 2. When the bearing sleeve or member 6 is thus installed, it will project partially through the opening 3 in 5 the boiler sheet and when it shall have been properly adjusted to insure accurate alinement of the bolt with its points of connection with the respective boiler sheets, it will be welded to the outer boiler sheet by a 10 weld 18 surrounding the body portion of the sleeve near its juncture with the enlarged head portion 11 of said sleeve.

Having fully described our invention what we claim as new and desire to secure 15 by Letters-Patent, is:—

1. In a staybolt structure, a bearing member having an internal seat for the head of a staybolt, said bearing member having its body portion rounded exteriorly lengthwise of the member and having a transversely rounded annular head at its outer end.
2. In a staybolt structure, a bearing member having an internal seat for the head of a staybolt, said bearing member having at one end an annular, transversely curved enlargement.
3. In a staybolt structure, the combination with a boiler sheet having an opening, 30 of a bearing member having an annular

transversely rounded enlargement near its outer end, said enlargement having an initial universally movable mounting on the wall of the opening, a staybolt having a head mounted in said bearing member, and a weld between a portion of said enlargement and a portion of the wall of the opening in the boiler sheet and uniting the bearing member to the boiler sheet.

4. In a staybolt structure, the combination with a boiler sheet having a bolt opening, of a bearing member provided at one end with an annular transversely curved enlargement to have an initial universally movable mounting in said opening, and a 40 staybolt having a head mounted in said bearing member.

5. In a staybolt structure, a bearing member having an annular transversely curved head at its outer end, and at its inner end 50 an exterior rounded portion and an interior seat for the head of a staybolt.

In testimony whereof, we have signed this specification in the presence of a subscribing witness.

BENJAMIN E. D. STAFFORD.
ETHAN I. DODDS.
